UNITED STATES PATENT OFFICE.

LEE ANDERSON, OF FOSTORIA, OHIO.

DESIGN FOR A GRAVE-COVER.

59,172.

Specification for Design.

Patented Oct. 4, 1921.

Application filed October 16, 1920. Serial No. 417,527. Term of patent 7 years.

To all whom it may concern:

Be it known that I, LEE ANDERSON, a citizen of the United States, and a resident of Fostoria, in the county of Seneca and State of Ohio, have invented a new, original, and ornamental Design for Grave-Covers, of which the following is a specification, reference being had to the accompanying drawing, forming part thereof.

Fig. 2 is a longitudinal sectional view thereof.

I claim:

The ornamental design for a grave cover, as shown.

LEE ANDERSON.
